UNITED STATES PATENT OFFICE.

COMMODORE L. GREER, OF LEAGUE CITY, TEXAS.

HANGER.

Application filed April 6, 1925. Serial No. 21,192.

This invention relates to new and useful improvements in a hanger.

One object of the invention is to provide a hanger, of the character described specifically designed for supporting a conductor, and more particularly designed for supporting a trolley wire from the messenger wire.

Another object of the invention is to provide a hanger which is flexible, or yieldable so as to permit the trolley wire to be elevated, relative to the messenger wire, without injury to the latter, or to the hanger.

A further feature of the invention resides in the provision of a hanger so constructed and attached to supporting messenger wire and the trolley wire, that the adjacent hangers will hold the parted ends of either wire, in case of breakage, of either wire, so that said parted ends may be readily reunited.

In the equipment of electric railways the messenger wire, or supporting wire for the trolley wire, is strung from pole to pole over the track and sags between the supporting poles and the trolley wire is suspended from it by hangers. It is desirable that the trolley wire be held against sagging, so that it will be comparatively straight and the hangers midway between the poles are shorter than those nearer the poles, the relative length of the hangers being such that the trolley wire will be held horizontal and in position not to sag.

As the trolley wheel passes along underneath the trolley wire this wire will be somewhat elevated and it is common practice to provide hangers which are rigid and fastened to the trolley wire with their upper ends provided with elongated vertical bearings to receive the messenger wire so that, as the trolley wheel passes along the trolley wire, the hangers will be permitted to move upwardly. This type of hanger is objectionable for the reason that it soon wears away the galvanized coating on the messenger wire and permits corrosion thereof, as well as the disintegration thereof, at the worn places, due to the electric current passing from the trolley wire along the hanger to the messenger wire. It is the chief object of this invention to provide a flexible, or yieldable type of hanger which will support the trolley wire, and permit the said movement thereof without injury to the supporting, or messenger wire.

With the above and other objects in view

this invention has particular relation to certain novel features of construction, operation and arrangement of parts an example of which is given in this specification and illustrated in the accompanying drawings, wherein:

Figure 1 shows an edge view of the hanger showing the wires in section.

Figure 2 shows a side view thereof, and

Figure 3 shows a vertical sectional view of the trolley wire clamp.

Referring now more particularly to the drawings, wherein like numerals of reference designate similar parts in each of the figures, the numeral 1 designates a supporting wire commonly known as the messenger wire, and the numeral 2 designates the trolley wire.

The messenger wire 1 is supported on poles, set a distance apart along the railway track, in the usual way. It is clear that this messenger wire will sag, somewhat, between, the poles. This wire is provided to support the trolley wire 2 which is suspended therefrom by the hangers. The trolley wire should be held against sagging so far as possible, and for that reason the hangers near the supporting poles, will be somewhat longer than those further away from said poles, the hangers varying in length, as required, to maintain the trolley wire as nearly straight as possible, but being otherwise similar.

Each hanger includes two wire clamps connected by links, or other flexible, or yieldable connection. As shown, and as a preferred construction, the messenger wire clamp 3 consists of an open ring 4 which surrounds the messenger wire 1 and which is formed with a depending eye 6, and opposite the eye the clamp has the outwardly turned, coinciding ends 7, 7 adapted to receive the clamp bolt 8, which passes through said ends and is held in place by the nut 8'.

The ring 4 will usually be clamped tightly on the messenger wire but in some cases it may be found necessary to give it a loose fit thereon to permit adjustment.

The trolley wire clamp, 9, may be of any form desired. A preferred form consists of two jaws 10, 10'. These jaws are clamped together by a clamp bolt 11, which passes through them and is held in place by a clamp nut 12. The lower ends of these jaws have inside transverse beads, or teeth, 13, 13 which fit into corresponding grooves 14, 14, in

opposite sides of the trolley wire. The underside of the trolley wire is clear, the clamps 9 being above said wire so as not to be struck by the trolley wheel.

5. The margins of the clamp jaw 10' have the side teeth 15, 15 adapted to project into opposing notches 16, 16, in the jaw 10 to hold said jaws in alignment.

There is an eye 17, formed with a shank 18 which fits between the jaws of the clamp 9, said clamp bolt 11 passing through said shank to secure said clamp. The eyes 6 and 17 receive the end links 19, 19 respectively, which in turn, are connected by one or more intermediate links 20, the numbers of connecting links depending on the length of the hanger desired.

As the trolley wheel passes along the trolley wire underneath the hangers it will 20 slightly elevate said trolley wire and the flexible connection between the wire clamps 3 and 9 will permit this without injury to the messenger wire.

In case either of the wires part, as sometimes occurs, the hangers will hold the parted ends and prevent them from moving far apart, or falling down, so that they may be quickly and easily reunited.

What I claim is:—

30 1. A hanger for suspending a trolley wire from a messenger wire and including a messenger wire clamp consisting of an open ring having a depending eye and whose upper ends coincide and are provided with a bolt hole to receive a securing bolt, a trolley wire clamp consisting of oppositely disposed jaws, a clamp bolt and nut connecting said jaws, the lower ends of the jaws having teeth adapted to fit into the corresponding grooves on opposite sides of the trolley wire, one of said jaws having inside notches and the other having projecting teeth which fit into said notches to secure said jaws in alignment and links flexibly connecting said clamps together.

40 2. A hanger for suspending a trolley wire from a messenger wire, said hanger including a messenger wire clamp and a trolley

wire clamp, said trolley wire clamp comprising two jaws and a clamp bolt for connecting the jaws together, the lower ends of said jaws having inside teeth adapted to fit into corresponding recesses on opposite sides of the trolley wire, the margins of one of said jaws having notches and the other jaw having projections which fit into said notches to maintain said jaws in alignment, an eye formed with a shank fitted between said jaws and through which said bolt passes and a flexible connecting member 60 connected at one end to said eye and at its other end to said messenger wire clamp.

3. A hanger for suspending a trolley wire from a messenger wire, said hanger including a messenger wire clamp and a trolley wire clamp, said trolley wire clamp comprising two jaws and a clamp bolt for connecting the jaws together, an inside tooth on the lower end of each jaw adapted to fit into a corresponding recess in a trolley 70 wire, a shank fitted between said jaws through which said bolt passes, said shank being formed with an eye, a flexible connecting member connected at one end to said eye and at its other end to said messenger wire clamp.

4. A hanger for suspending a trolley wire from a messenger wire, said hanger including a messenger wire clamp and a trolley wire clamp, said trolley wire clamp comprising two jaws and a clamp bolt for connecting the jaws together, an inside tooth on the lower end of each jaw adapted to fit into a corresponding recess in a trolley wire, a shank fitted between said jaws 80 through which said bolt passes, said shank being formed with an eye, a flexible connecting member connected at one end to said eye and at its other end to said messenger wire clamp, one of said jaws having an inside notch and a projection carried by the other jaw and fitted into said notch 90 to hold said jaws in alignment.

In testimony whereof I have signed my name.

COMMODORE L. GREER.
